UNITED STATES PATENT OFFICE.

WILLIAM J. HOLCOMB, OF BELLEFONTAINE, OHIO.

COMBINATION-LOCK FOR CAR-DOORS.

1,401,701.

Specification of Letters Patent. Patented Dec. 27, 1921.

Application filed November 2, 1920 Serial No. 421,377.

To all whom it may concern:

Be it known that I, WILLIAM J. HOLCOMB, a citizen of the United States, residing at Bellefontaine, in the county of Logan and 5 State of Ohio, have invented certain new and useful Improvements in Combination-Locks for Car-Doors; and I do hereby declare the following to be a full, clear, and exact description of the invention, such as will enable 10 others skilled in the art to which it appertains to make and use the same.

The invention relates to a combination lock for car doors and the object is to provide a device which shall be especially effective for 15 the purpose specified, and which can be opened only by an individual having knowledge of the combination, and after the individual tumblers of the lock have been set in the position required for permitting the 20 movement of a three part bolt to inoperative position.

A further object is to provide, in a lock of the type indicated, a plurality of tumblers each mounted on a separate axis, and a three 25 part bolt for coöperation with the tumblers so mounted.

A still further object is to provide, in connection with a notched bar, a plurality of dogs coöperating with the bar, a three part 30 locking bolt controlling the dogs and acting to release them from the notched bar, and a plurality of tumblers each mounted on a separate axis, the movement of the bolt to inoperative position for releasing the dog, de- 35 pending upon the relative position of the tumblers.

A still further object is to provide for throwing the bolts by the use of a key, with which the dials may also be set, and to pro- 40 vide an independent bolt operating device controlled by rotary or longitudinal movement, one element of the last named device constituting a seal bar.

With the foregoing and other objects in 45 view, the invention consists in the novel construction, combination and arrangement of elements hereinafter described and claimed, it being understood that modifications or variations in construction may be made within 50 the scope of the claims, without departing from the spirit of the invention.

In the accompanying drawings:—

Figure 1 is a view of the lock in elevation, as applied to the side of a box car, the pivot-

ally mounted locking element being shown 55 at the right and mounted on the car door.

Fig. 2 is an end elevation of the lock cas- 60 ing, looking from the left in Fig. 1.

Fig. 3 is a view showing the operative ele- 65 ments in elevation, the face plate of the cas- ing being removed.

Fig. 4 is a similar view, the three part bolt having been thrown, and the notched bar in the lower portion of the view being disen- 70 gaged.

Fig. 5 is a horizontal section, on line 5—5 of Fig. 3.

Figs. 6 and 7 are horizontal sections of the 75 devices for throwing the three part bolt.

Fig. 8 is a section on line 8—8 of Fig. 7.

Fig. 9 is a detail of construction described 80 below.

The reference number 10 indicates the cas- 85 ing *per se* of the lock, to be mounted on the side of a car, and the face plate of the lock 75 is designated 12. The tumblers are shown at 14, 15 and 16, and are provided with notches 17, each tumbler being further pro- 90 vided with a deep notch or slot 18. These tumblers are rotated by a key 20 having a socket engaging the square ends 21 of the pins 22, these pins having connection with the dial plates.

The dial plates 24, 25 and 26 are provided 85 with a series of numbers, as shown, and these numbers are to be set in a predetermined re- 95 lation, in order that all of the slots 18 may be so positioned that the bolt will be permitted to operate for releasing the dogs referred to below.

A bar 30 carries pins 31 and 32, for coöper- 90 eration with the slots 18 of members 14 and 16, and a vertical bar 34 carries a pin 35 for coöperation with the slot 18 of tumbler 15. The bar 34, which has one end pivoted, is 95 provided with a slot 36, and a pin or screw 37 passing through the bar 30 coöperates with the slot, and causes the bar 30 to be thrown when the bar 34 is moved from the position shown in Fig. 3 to that shown in Fig. 4. As 100 the result of this construction, all of the pins coöperating with the slots 18 move at the same time, and if the tumblers are in correct position for opening the lock, the pins will of course enter the slots.

Dogs 41 and 42 engage the notches 43 of 105 the bar 44, and the dogs are controlled by an- gles levers 45 and 46 pivotally connected with

bar 30, so that the dogs are released from bar 44 when the tumblers are in the position just indicated, and when the bars 30 and 34 are thrown. For convenience these bars 30 and 34 are together termed a three part bolt.

The notched bar 44 is pivotally connected with the car door by straps 44', and swings downwardly to vertical position when released from the lock.

- 10 The upper end of bar 34 projects into a slot 47 in sliding bar 48, and threaded into the end of the latter is a seal bar or stem 48^a, the shank and threaded portion of which passes loosely through a block 49.
- 15 Sliding bar 48 is guided by threaded pins 48'.

The laterally extending stationary block 49 has a transverse slot 50 therein accommodating a collar 51 loosely mounted on the seal bar. A pin 52 may be passed through registering apertures in bar 48 and the threaded portion of the seal bar, preventing the rotation and withdrawal of this bar, longitudinal movement of element 48 and 25 the seal bar being permitted for shifting the three part bolt of the lock.

If this pin 52 is withdrawn and passed through registering apertures in the collar and the seal bar, the collar will prevent longitudinal movement of the seal bar, but will permit of rotation, and the threaded portion coöperating with the threaded bore of the member 48 will permit that bar to be shifted by imparting rotary movement to 35 the head 54.

If the seal bar and operating member are withdrawn by removing the pin 52, and unscrewing the end of this bar from the bar 48, the three part bolt may be operated by 40 causing key 20 to engage the square end 21' of the pin 30' which serves as a pivotal element for bar 34.

The flexible element 55 of seal 56 may be passed through registering apertures of the 45 element 49 and the seal bar 48^a.

Having thus described the invention, what I claim is:—

1. In a device of the class described, a casing, a plurality of tumblers mounted therein in different planes, an element adapted to be locked in a predetermined position within said casing, locking members for engagement with said element, locking members for operating said members, bars adapted to 50 control said pivoted operating members, said tumblers being adapted at times to prevent operation of said bars, and operating means for said bars.
2. In a device of the class described, a casing, tumblers mounted therein and provided with radial slots, an element adapted to be locked in a predetermined position within said casing, pivoted locking members for engagement with said elements, bars for controlling the operation of said pivoted lock- 60

ing members, pins carried by said bars and adapted for engagement at times in said slots of the tumblers, and an operating member for said bars, said operating member being adapted to have a seal extended therethrough. 70

3. In a device of the class described, a casing, tumblers mounted therein on independent axes and each including a radial slot, a bar carrying a pin positioned to enter the slot of one of the tumblers, a second bar and pins mounted thereon for entering the slots of the other tumblers when the latter are in a predetermined position, means for pivotally connecting the bars, an element to be locked, an engaging device for said element, and means connecting the engaging device with one of the bars. 75

4. In a device of the class described, a casing, tumblers mounted therein on independent axes and each including a radial slot, a bar and a pin thereon, means for pivotally mounting the bar, the pin coöperating with the slot of one of the tumblers, a second bar pivotally connected with that first named, pins carried by the second bar for coöperation with the slots of the remaining tumblers when the latter are in a predetermined relation, an element to be locked, an engaging device coöperating therewith, 95 an element pivotally connected with the engaging device and with one of the aforesaid bars, and a third bar pivotally connected with the bar first named. 90

5. In a device of the class described, a casing, tumblers mounted therein, and each having a radial slot, a plurality of elements pivotally connected, disposed at an angle with each other, and constituting a three part locking bolt for coöperation with the 100 tumblers, and a slideable device for controlling the three part bolt.

6. In a device of the class described, a casing, tumblers mounted therein, and each having a radial slot, a plurality of elements 110 pivotally connected, disposed at an angle with each other, and constituting a three part locking bolt for coöperation with the tumblers, and a slideable device for controlling the three part bolt, and a device constituting a seal bar for operating the slideable device. 115

7. In a device of the class described, a casing, tumblers mounted therein, and each having a radial slot, a plurality of elements 120 pivotally connected, disposed at an angle with each other, and constituting a three part locking bolt for coöperation with the tumblers, a slideable device for controlling the three part bolt, and an element connected with the slideable device for operating the latter by rotary or longitudinal movement. 125

8. In a device of the class described, a tumbler, a locking element directly coöper- 130

ating therewith, and means for controlling said locking element and comprising a bar, a stem threaded into the end thereof, a stationary member having a bore for guiding the threaded element, said stationary member having a slot therein, a collar within the slot, normally loose on the stem and engaging the walls of the slot, and a pin for connecting the collar with the stem, permitting

the bar to be shifted longitudinally by rotating the threaded stem with reference thereto.

In testimony whereof I affix my signature in presence of two witnesses.

WILLIAM J. HOLCOMB.
